UNITED STATES PATENT OFFICE.

ALBIN BERTHOLD HELBIG, OF BERLIN, GERMANY.

WATER-COOLED FURNACE WALL.

Application filed May 18, 1925, Serial No. 31,229, and in Germany January 10, 1925.

This invention relates to water cooled furnace walls, and has for its primary object to provide a furnace wall structure of this character whereby rapid deterioration of the wall 5 by the intense heat will be prevented. The present improvements generally comprehend a fire brick wall for furnaces of that general type in which cooling tubes are provided in the interior of the wall. It has heretofore 10 been generally supposed to be impossible to build such a furnace wall which will be sufficiently elastic to allow the proper and necessary expansion and therefore, since such large areas of the brick work are exposed to 15 the radiation of the fire, it has been found necessary in furnaces of modern design to provide numerous expansion joints in such furnace walls. With my present improvements however, I provide a wall that is in 20 effect a homogenous structure, no mortar joints being provided. At the same time the new wall structure is exceedingly simple and may be easily erected at minimum expense. It is also quite elastic and insensible to variations of temperature.

It is another object of my invention to provide a firebrick wall for furnaces of the above character, which under working conditions will be absolutely gas proof and will at all 30 times retain its original position.

With the above and other objects in view, the invention consists in the improved furnace wall structure and in the form, construction and relative arrangement of the several 35 parts as will be hereinafter more fully described, illustrated in the accompanying drawings, and subsequently incorporated in the subjoined claims.

In the drawings, wherein I have illustrated 40 several simple and practical embodiments of the invention, and in which similar reference characters designate corresponding parts throughout the several views,

Figure 1 is a transverse section through a 45 portion of the furnace wall;

Fig. 2 is a front elevation;

Fig. 3 is a side elevation of the wall;

Figs. 4 and 5 illustrate the application of 50 my present improvements to a Babcock-Wilcox boiler, and

Figs. 6 and 7 illustrate another application of the invention to a Stirling boiler.

The walls of the furnace structure are lined with or have incorporated therein, a multiplicity of spaced water tubes 1 which are properly connected to the boiler and to each

other. These water tubes serve first to cool the refractory firebrick and maintain the same at a temperature below the fusing point, quickly carrying away the heat radiated into these brick, and secondly said tubes serve as supports for the wall structure, and by means thereof it is possible to appreciably reduce the thickness of the wall without seriously 60 affecting its stability. 65

Between the several tubes, the firebricks 2 are inserted, there being sufficient play to allow for expansion. Preferably the bricks are made as small as possible so that the heat radiated to them from the fire will be very 70 quickly transmitted to the boiler. Some of these bricks are provided with a transversely extending opening therethrough for a rod 3. A fastening screw 4 is connected to each end of this rod and imbedded in the firebrick. As 75 will be seen from reference to Fig. 3 of the drawings, each brick is provided on its top and bottom with transverse shoulders and the adjacent brick between the tubes 1 are arranged in reverse position so that the shoulders 80 of each brick will engage the shoulders of the bricks above and below it. The bricks thus rest evenly upon one another. It will also be seen by reference to Fig. 1 of the drawings, that each brick has a relatively wide portion extending at its opposite sides partially around the tubes 1, and a relatively narrow portion projecting between the tubes. Between these narrow portions of the bricks 85 the brick 5 are arranged and seated against 90 the tubes 1. Since there are no mortar joints employed between the bricks, the bricks 2 and 5 may expand relatively to each other.

The outer face of the wall, remote from the combustion space of the furnace has an elastic 95 insulating material 6 applied thereon and covers the joints between the bricks. Over this insulating material, a cover plate 7 is arranged. This plate may consist of ferrocement, iron or any other desired metal, and is tightly held in place by suitable nuts threaded on the ends of the bolts 4. After 100 these nuts have been tightened up, the firebricks are held pressed against the tubes 1 and this pressure may be easily regulated and does not increase during the heating of the brick. The brick 2 are directly heated from the furnace fire and are therefore, of a higher 105 temperature than the brick 5 which are only indirectly heated through contact with the brick 2. This difference in temperature of the bricks is compensated for by the elasticity 110

of the insulating material 6. Thus, the wall is relieved of all strains and stresses which might otherwise be caused by expansion of the wall brick due to high temperatures.

5 Owing to the breaking of the joints between the bricks 2, these joints are more effectively caulked or sealed by the insulating material 6.

By inspection of Fig. 1 it will be seen that the bricks 2 project to both sides of the water 10 pipes 1 these brick having relatively wide ends which extend partly around and partly overlap the pipes 2 and the faces of these relatively wide ends make up the inner or furnace side of the wall built with these bricks.

15 The wide ends of the bricks have slight spaces between them going in as far as the pipes 1. The relatively narrow body of each of these bricks passes between the pipes 1 in the opposite direction and the extremities covered

20 By the insulating material 6 and plate 7 make up the outer side of the furnace; the bricks 5 being placed between the pipes 1 and insulation 6; and the insulation 6 and plate 7 being held fast by the attaching elements 4.

25 The plate 7 when engaged by the attaching means 4 serves as a means for uniting the bricks together.

By clamping the wall bricks against the water tubes in the manner above explained, 30 the lower bricks are partially relieved of the weight of the wall structure and the bricks are very efficiently cooled so that they will retain their physical qualities and their resistance to stress or strain.

35 In Figs. 4 to 7 inclusive, I have shown the side and top walls of the furnace chambers provided with air chambers 9. While the heat is well retained within the furnace chamber by the walls, some of it may pass through 40 the wall structure into these air chambers. From the air chambers the heated air is discharged into the furnace and may be used alternately as primary and secondary air.

In Figs. 4 and 5 I have illustrated the 45 present improvements as applied to a Babcock-Wilcox boiler generally indicated at 10.

The mixture of primary air and coal is introduced to the furnace chamber through the front wall 11, and said wall is perforated or 50 provided with openings through which air is forced under pressure into the combustion stream from the air chamber 12. The air in this chamber serves to cool the wall structure. The upper portion of the furnace is occupied 55 mostly by the boiler tubes and therefore, only a relatively small part as at 13, must be water cooled which is also the case with the other three sides and the bottom of the furnace. In this type of furnace, water tubes are ele- 60 vated above the bottom thereof to form a water screen 14 from beneath which the ashes are removed mechanically in granulated form.

In Figs. 6 and 7 of the drawings I have 65 shown the application of my present improve-

ments to a Stirling boiler indicated generally at 15, this installation being practically the same as that above referred to, with the exception that the water tubes are imbedded in the bottom wall of the furnace which is elevated so that the residue or ashes may be withdrawn in a liquid condition.

70 While I have above described an embodiment of the invention which has been found very satisfactory in practical use, it will nevertheless be understood that the several features thereof may also be incorporated in various other alternative structures, and I accordingly reserve the privilege of adopting 75 all such legitimate changes as may be fairly embodied within the spirit and scope of the invention as claimed.

I claim:

1. In a wall structure for furnaces, spaced 80 water tubes, firebrick arranged between said tubes and projecting from opposite sides thereof, said firebrick provided on their opposite side faces with horizontal shoulders for interlocking engagement with each other, additional firebrick arranged upon one side of 85 said tubes between said first-named firebrick, an elastic insulating sheet covering the outer face of the wall structure, a plate engaged upon said insulating sheet, and fastening devices connected with certain of the first-named bricks and extending through said insulating sheet and the plate and thereby 90 uniting the bricks in assembled relation while permitting of their relative expansion under 95 heat.

100 2. In a wall structure for furnaces, a plurality of water tubes, firebricks between the tubes in contact with one another and projecting beyond the tubes at both ends, additional firebricks placed between the first-named bricks, the latter having enlarged extremities partly overlapping the tubes on the furnace side of the wall; the outer ends of some of the first-named bricks having attaching elements, and means extending over the outer face of the wall and engaged by said attaching elements to hold said bricks in assembled relation.

105 3. In a wall for furnaces, a row of water tubes, firebricks between said tubes, arranged in contact with one another, said firebricks having shoulders for engagement with each other, additional firebricks between the first-named bricks and engaging one side of said tubes, said first-named bricks being shaped to bind against the tubes adjacent their ends on the furnace side of the wall, and projecting at both ends from said row of tubes, some of said first-named bricks having attaching elements and means upon the outside of the wall and secured by said attaching elements to retain the bricks in position.

110 4. In a wall for furnaces, a row of water pipes, firebricks between said pipes arranged in contact with one another, said bricks hav-

- ing relatively narrow portions extending beyond the pipes toward the outer face of the wall, and relatively wide ends partly overlapping said pipes on the furnace side of the 5 wall, additional bricks between the narrow portions of the first named bricks, some of the first named bricks carrying fastening elements, elastic material over the outer side of said wall, and a plate covering the elastic 10 material and secured by said fastening elements.
5. In a wall for furnaces, a plurality of water pipes, firebricks between said pipes and arranged in contact with one another, 15 said firebricks extending beyond the pipes at both ends, said firebricks having their ends on the furnace side of said wall enlarged and partly overlapping said pipes, the enlarged ends having spaces between them to expose 20 parts of said pipes, the remaining portions of said bricks being relatively narrow and extending between the pipes in the opposite direction toward the outer side of the wall, additional bricks between the first-named 25 bricks and engaging said tubes and lying be-
- tween same and the opposite or outer side of said wall, elastic material arranged over the outer side of the wall, fastening elements carried by some of said first named bricks, and a rigid plate over said elastic material 30 secured by said elements.
6. In a wall for furnaces a row of water pipes, firebricks between the pipes arranged in contact with one another and extending at both sides of said row, said bricks having their ends on the furnace side of the wall shaped to bind against the pipes, said ends being spaced apart to expose portions of said pipes, additional firebricks between the first named bricks and abutting the pipes, elastic material engaging said additional bricks and the first named bricks on the outer side of said wall, certain of said first named bricks carrying fastening elements, and a plate 35 covering the elastic material and secured by 40 said fastening elements.

In testimony that I claim the foregoing as my invention, I have signed my name hereto.

ALBIN BERTHOLD HELBIG.
